Richard F. Scully, Hopewell Junction, N.Y., assignor to International Business Machines Corporation, New York, N.Y., a corporation of New York
Filed Apr. 30, 1963, Ser. No. 276,720
9 Claims. (Cl. 234—19)

This invention relates to the feeding of paper and more particularly the control of a carriage feeding paper to a printing or punching position.

On a typewriter or punch the position of the platen carriage or card carriage is now controlled by fixed tabulator stops, programs and the like. Once these fixed controls are set up for a particular format such as a bill, statement or card form, they remain fixed and must be altered to fit any change. The selection of position in some instances is made by a separate set of tabulating keys.

It is the principal object of this invention to provide a flexible tabulating device that can be controlled from a standard keyboard.

Another object is to provide a simple circuit that can readily be adapted to control the feeding of a document to a definite position.

A further object is to provide a cheap and effective method of tabulation.

The foregoing and other objects, features and advantages of the invention will be apparent from the following more particular description of the preferred embodiment of the invention, as illustrated in the accompanying drawings.

In the drawings:

FIGS. 1-4 inclusive when combined as shown in FIG. 5 form a schematic of the invention as adapted to a card punch.

FIG. 6 is an isometric view of a card punch using the invention.

FIG. 7 is a schematic of the card feed drive.

A preferred embodiment of the invention will be described as adapted to an eighty column card punch of the type shown in detail in the U.S. Patent to E. W. Gardinor et al., 2,647,581 issued August 4, 1953. It will be apparent that the invention could be used with any form of key operated business machine wherein it is necessary to control the positioning of a document with respect to a point at which data is to be entered therein.

Only those features of the punch disclosed in the above patent will be described that are needed for an understanding of the invention. The punch (FIGS. 6 and 7) comprises a card magazine 90 from which a card is fed by a transporting means past a set of punches 91 to a reading station 92 and thence to a hopper 93. The punches are selectively operated from a keyboard 94. As normally controlled, a drum 95 on which a punched card is wrapped, programs the feeding of the card and certain functions such as automatically skipping certain fields or columns of the card duplicating certain data from the preceding card, spacing the card, etc. All of the functions are fixed by the program card to occur when preselected columns of the card are under the punches. The punches are selected for operation from the keyboard when one of the keys 381 closes a circuit to actuate a solenoid that places an interposer between an operating member and a punch. Operation of the member will cause the associated punch 91 to perforate the card. The card is transported past the punch position by feed rolls 97 that are controlled by an escapement 100 which permits the rolls to advance the card one column for each punch operation. The keys mechanically control one or more of a series of rods (not shown—349 in the above patent) which in turn effects the closing

of contacts that will operate the punch interposer magnet 188 corresponding to the key operated. The rods also close contacts to actuate an escapement magnet 104 starting a columnar movement of the card and they also open a contact to restore the keyboard to normal. The motor 105 continuously drives the gear 106 which upon operation of clutch 107 will drive the gear train 108-112 which will rotate the friction rolls 113, 114 and 115 to transport cards past the punching and reading lines 116 and 117.

Only as much of the operating circuit of the punch needed for an understanding of the invention is disclosed in the schematic comprising FIGS. 1-4. In the following description, whenever the reference numerals depart from chronological order, it may be assumed that the numeral is that used for a like part in the above patent, i.e., 381 designates numeral keys in both application and patent. Also in order to simplify the specification wherever contacts are mentioned, a normally closed contact will be referred to as NC contact and transferred contacts as T contacts. Also a pick or operating winding of a relay will be called the P winding and the hold winding the H winding.

The dash lines 10 enclose the keyboard comprising keys 381. Operation of one of the keys such as the "14" key will close a circuit from zero voltage, lead 11, normally closed KEYBOARD RESTORE contact 352-1, lead 12, "4" key 381, normally closed contact 14-4 of Entry relay 14, through "4" interposer magnet 188, lead 16, to positive voltage lead 17. The operation of the "4" interposer magnet sets an interposer at the "4" punch and actuates a bail (not shown—192 in above patent) which will close contact 195, this will in turn cause tube T-4 to conduct over a circuit from "O" lead 11, contact 195, contact 49-4, rectifier, contact 46-3, lead 18, resistance 20, tube T-4, lead 21, through ESCAPE magnet 104 over leads 22 and 23, to plus lead 17. The ESCAPE magnet will operate and effect a feed to the next column and also through its contact 104-1, a circuit will be closed from lead 11, lead 24, through the contact, lead 25, winding of relay 46, leads 23 and 17, to positive potential; operating relay 46 which at its contact 46-3 will open the circuit for the ESCAPE magnet. During this operation, the KEYBOARD RESTORE magnet 352 has been operated through cam CF5, and opens its contact 352-1, disabling the keyboard and releasing all the keys. Upon release of magnet 352 the keyboard is ready for a second entry.

All of the foregoing describes a normal operation of the punch. If the operator now wishes to enter data in a particular column, for instance the forty fifth, the tabulating is started by closing TAB. SW. 26. This will complete a circuit from lead 11 through a cam operated contact CF3, switch 26, through pick winding of a latch relay 27 to positive overleads 28 and 23 operating the relay 27. This relay (FIG. 1) will, at its contacts 27-1 to 27-5 inclusive, open the circuits from keys controlling such functions as automatic space, skip, etc. that would interfere with the column selection if accidentally selected by the operator or the program drum. The circuits are not completed but are only indicated since they have no part in the present invention.

The circuit is now ready for tabulating to column forty-five. The operator depresses and holds down ENTRY key 30 (FIG. 1) which will close a circuit from lead 11, through the winding of relay 14, over leads 31 and 23, to lead 17, operating the relay 14. This relay will transfer its contacts thereby disconnecting the keyboard from the interposer magnets 188 and connecting it to the matrix in FIG. 2.

With the ENTRY Key held closed the operator now depresses the "4" key 381 closing a circuit from lead 11, contact 352-1, lead 12, T contact 14-4, lead 32, NC con-

tact 33-4 of ERROR relay 33, NC contact 34-4 of SECOND KEY STROKE relay 34, lead 35, through the P winding of TENS relay T4, to lead 17 operating the relay. The relay then locks up from lead 11, lead 42, NC contact 45-2, lead 36, contact T4-1, through the H winding of the relay to lead 17. This will prepare circuits of the EMITTER 40 that will be completed by the UNITS relays.

Simultaneously a circuit is closed by the "4" key over the above circuit to lead 35 (FIG. 2), thence through diode 38, over lead 41, through the P winding of SECOND KEY STROKE relay 34 that operates and locks up over a circuit from lead 11, lead 42, NC contact 45-4, lead 43, T contact 34-10, through the H winding of relay 34, over lead 44, to lead 17. A circuit is also closed through diode 38 over lead 41, through the winding of the KEYBOARD RESTORE magnet 352, to lead 17 thus opening NC contact 352-1 (FIG. 1) and removing current from the keyboard thereby restoring all operated keys.

The operation of relay 34 will transfer the circuits such as that traced above for the TENS relay T4 to circuits for operating the UNIT relays from the keyboard. The operator now depresses the "5" key closing a circuit from lead, 11NC contact 352-1 again closed (since the relay 352 released upon restoring the keyboard) lead 12, "5" key, T contact 14-5, lead 47, NC contact 33-5, T contact 34-5, over two circuits one through diode 48 lead 50, NC contact T8-2, through the winding of the UNITS relay U-4, lead 51, to lead 17, the other through diode 52, lead 53, NC contact T8-4, through UNITS relay U-1 to lead 17. The two relays comprise the binary code for five, i.e. four and one.

A circuit is now closed from lead 11 (FIG. 3), through cam switch P5, lead 54, T contact 27-1, lead 55, T contact U1-1, NC contact U8-1, T contact U4-3, NC contact U2-1, lead 56, NC contacts T1-5, T2-5, and T3-5, T contact T4-5, over lead 57 to the forty fifth contact on the EMITTER 40.

At the same time that relays U1 and U4 are operated, a circuit is closed through diodes 58 and 60, lead 61, NC contact 45-3, lead 62, NC contact 46-3, lead 18, firing tube T4 which operates the ESCAPE magnet 104. This releases the escapement for the card feed rolls and closes T contact 104-1 which operates relay 46 closing the T contact 46-3. This completes a circuit to fire tube T7 which operates the PUNCH CLUTCH magnet 204, causing the punch to go through one cycle and advance the card one column. The NC contact 46-3 upon opening released tube T4 and released the ESCAPE magnet holding the card feed to one column. This operation is described in detail in the above patent.

Since the "5" key is locked down in the keyboard the circuits for the ESCAPE and PUNCH CLUTCH will continue to be made and broken thus advancing the card column by column. The EMITTER 40 being synchronized with the card feed, the brush 64 will sweep the contacts until it reaches the forty-fifth contact at which time the circuit formerly traced through cam switch P5, NC contacts T1-5, T2-5 and T3-5 and T contact T4-5 will connect zero voltage through the winding of STOP relay 45 over leads 66 and 23 to positive lead 17 operating the STOP relay 45. This relay at its T contact 45-3, opens the circuit to the ESCAPE magnet 104 preventing further feeding of the card. It opens the holding circuit for the T4 relay thereby opening the path through the matrix to the forty fifth contact.

The operator now releases the ENTRY Key 30 releasing the ENTRY relay 14 which in turn closes a circuit for operating the KEYBOARD RESTORE magnet 352 (FIG. 2) from lead 11, through NC contact 352-1, lead 12, through key "4," T contact 14-4, NC contact 33-4, lead 67, NC contact 14-10, lead 68, winding of relay 352 to lead 17. This opens NC contact 352-1 (FIG. 1) removing zero voltage from the keyboard releasing all keys. This also permits the punch to return to normal opera-

tion since the lock trip winding LT of relay 27 is actuated over a circuit from lead 11, lead 42, T contact 45-1, lead 70 through the LT winding, over leads 28 and 23, to lead 17. This releases the mechanical lock on relay 27 permitting it to release opening the circuit over lead 55 to the decoding matrix.

Should the operator attempt to select a column ninety or even eighty one, an error circuit will be set up as follows. Depressing the "9" key will close a circuit from lead 11, contact 352-1, lead 12, "9" key, T contact 14-9, NC contact 33-9, NC contact 34-9, lead 71, through winding of ERROR relay 33, lead 44 to lead 17. The operation of this relay will open all the contacts of relay 33 preventing the selection of any T relay. The KEYBOARD RESTORE magnet 352 is also operated through the T contact 33-9, over leads 67 and 68, releasing all operated keys.

Should a column eighty eight be selected, the operation of the first "8" key will operate relay T8 (FIG. 2) which will open all leads to relays U1, U2, U4 and U8, thereby preventing their operation. Also a circuit is closed at all T contacts of relay T8 that will operate the ERROR relay 33 over leads 72 and 44. This closes the T contacts of relay 33 completing a circuit from the operated key over lead 67, contact 14-10, lead 68, through the KEYBOARD RESTORE magnet 352, to restore all operated keys indicating to the operator that an error has been made.

While the invention has been particularly shown and described with reference to a preferred embodiment thereof, it will be understood by those skilled in the art that the foregoing and other changes in form and details may be made therein without departing from the spirit and scope of the invention.

What is claimed is:

1. In a keyboard operated recorder; means for transporting a record divided into columns of index positions, step by step past a recording point; means for driving said transporting means; circuit closing means having a plurality of terminals, said closing means acting sequentially in synchronism with said transporting means; a memory means set by a key in said keyboard in accord with the tens digit designating one of said columns; a selecting circuit set by a second key in said keyboard, designating the units digit of said selected column, said circuit extending through said memory means to a terminal of said circuit closing means corresponding to the selected column; and means to disable said transporting means when said selected terminal has been reached.
2. In a keyboard operated recorder; means for transporting a record, divided into columns of index positions, step by step past a recording point; means for driving said transporting means; an emitter having a plurality of terminals, said emitter acting sequentially in synchronism with said transporting means; a memory means set by a key in said keyboard in accord with the tens digit designating one of said columns; a selecting circuit set by a second key in said keyboard designating the units digit of said selected column, said circuit extending through said memory means to a terminal of said emitter corresponding to the selected column; and means to disable said transporting means when said selected terminal on said emitter has been reached.
3. In a keyboard operated recorder; means for transporting a record, divided into columns of index positions, step by step past a recording point; means for driving said transporting means; an emitter having a plurality of terminals, said emitter acting sequentially in synchronism with said transporting means; a plurality of circuit closing means, one of which is

- set by a key in said keyboard in accord with the tens digit designating one of said columns; a selecting circuit set by a second key in said keyboard designating the units digit of said selected column, said circuit extending through said selected circuit closing means to a terminal of said emitter corresponding to the selected column; and means to disable said transporting means when said selected terminal on said emitter has been reached.
4. In a keyboard operated recorder; means for transporting a record step by step past a recording position; means for driving said transporting means; circuit closing means having a plurality of terminals, said closing means acting sequentially in synchronism with said transporting means; a memory means set by a key in said keyboard in accord with a selected number of step movements of said transporting means; a selected circuit set by a second key in said keyboard extending through said memory means to a terminal of said circuit closing means; and means to disable said transporting means when said selected terminal has been reached by said circuit closing means.
5. In a keyboard operated recorder; means for transporting a record divided into columns of index positions step by step past a recording point; means for driving said transporting means; an emitter having a plurality of terminals, said emitter acting sequentially in synchronism with said transporting means; a plurality of relays, one of which is actuated by a key in said keyboard in accord with the tens digit designating one of said columns, a selecting circuit, closed by a second key in said keyboard designating the units digit of one of said columns, said circuit extending through the closed contacts of said selected relay to a terminal of said emitter corresponding to the selected column, and means to disable said transporting means when said selected terminal has been reached.
6. A keyboard operated punch; feed rolls for transporting a card divided into columns of index positions; means for driving said feed rolls step by step; a plurality of keys in said keyboard controlling circuits for selectively actuating interposer magnets for controlling said punch; a plurality of tens relays equal in number to said interposers selectively operated over circuits from said keys; a switching means for selectively transferring said key circuits from connection to said interposers to circuits to said relays; a decoding matrix of units relays; an emitter driven in synchronism with said feed rolls; a control relay actuated in parallel with any one of said tens relays, acting to transfer said key circuits from said tens relays to said units relays; a stop relay connected to the brush of said emitter; a circuit closed by one of said keys to operate one or more of said tens relays; a second circuit in parallel with said units relays for actuating said driving means to effect the movement of said feed rolls from column to column; and a third circuit through the contacts of said units relays, contacts of the selected tens relay, contact of the emitter corresponding to the selected column and the stop relay opening the circuits to said control means, stopping the feed rolls at the selected column.
7. A keyboard operated punch; feed rolls for transporting a card divided into columns of index positions, an escapement for controlling feed rolls;

- a magnet for controlling said escapement; a continuous drive for said feed rolls; a clutch magnet for controlling said drive; a plurality of keys in said keyboard controlling circuits for selectively actuating interposer magnets for controlling said punch; a plurality of circuit closing means equal in number to said interposers selectively operated over circuits from said keys; a switch in said circuits for selectively transferring said key circuits from connection to said interposers to circuits to said circuit closing means; a plurality of second circuit closing means forming a decoding matrix; an emitter driven in synchronism with said feed rolls; a control relay actuated in parallel with any one of said first circuit closing means, acting to transfer said key circuits from said first to said second circuit closing means; a stop relay connected to the brush of said emitter; a circuit closed by one of said keys to operate one or more of said first circuit closing means; a second circuit in parallel with said second circuit for closing means for actuating said escapement magnet and clutch magnet to control the driving of said feed rolls from column to column; and a third circuit through said second circuit closing means, and through the selected one of said first circuit closing means, contact of the emitter corresponding to the selected column and contacts of the stop relay opening the circuit to the escapement and clutch magnets stopping the feed rolls at the selected column.
8. A keyboard operated punch; feed rolls for transporting a card divided into columns of index positions, means for driving said feed rolls step by step; a plurality of keys in said keyboard controlling circuits for selectively actuating interposer magnets for controlling said punch; a plurality of circuit closing means equal in number to said interposers selectively operated over circuits from said keys; means for selectively transferring said key circuits from connection to said interposers, to circuits to said circuit closing means; a plurality of second circuit closing means forming a decoding matrix; an emitter driven in synchronism with said feed rolls; a control relay actuated in parallel with any one of said first circuit means, acting to transfer said key circuits from said first to said second circuit closing means; a stop relay connected to the brush of said emitter; a circuit closed by one of said keys to operate one or more of said first circuit closing means; a second circuit in parallel with said second circuit closing means for actuating said driving means to effect the movement of said card from column to column; and a third circuit through said second circuit closing means and through the selected one of said first circuit closing means, contact of the emitter corresponding to the selected column and contacts of the stop relay, opening the circuit to said driving means and stopping the card at the selected column.
9. A keyboard operated punch; feed rolls for transporting a card divided into columns of index positions; an escapement for controlling said feed rolls; a magnet for controlling said escapement; a continuous drive for said feed rolls; a clutch magnet for controlling said drive; a plurality of keys in said keyboard controlling circuits for selectively actuating interposer magnets for controlling said punch; a plurality of tens relays equal in number to said inter-

posers selectively operated over circuits from said keys;
 a switch in said circuits for selectively transferring said key circuits from connection to said interposers to circuits to said relays;
 a locking circuit for each of said relays;
 a decoding matrix of units relays;
 an emitter driven in synchronism with said feed rolls;
 a control relay actuated in parallel with any one of said tens relays acting to transfer said key circuits 10 from said tens relays to said units relays;
 a stop relay connected to the brush of said emitter;
 a circuit closed by one of said keys to operate one or more of said tens relays;
 a second circuit in parallel with said units relays for 15 actuating said escapement magnet and clutch magnet

to control the movement of said feed rolls column by column; and
 a third circuit through the contacts of said units relays, contacts of the selected tens relay, contact of the emitter corresponding to the selected column and contacts of the stop relay opening the circuits to the escapement and clutch magnets stopping the feed rolls at the selected column.
